ONE-PIECE SOFT RUBBER PLUG

Clarence P. Berolzheimer, Chicago Heights, Ill.

Application May 25, 1931, Serial No. 539,689

12 Claims. (CL 173—361)

This invention relates to an improved one-piece soft-rubber plug, particularly for electrical connections, and has for one of its principal objects the provision of a plug of this sort which can be simply and economically manufactured, and which furthermore, will be completely satisfactory from a commercial and an industrial standpoint.

One of the important objects of this invention is the provision of a one-piece plug for electrical connections, the body of which plug is composed of soft rubber or the like, rendering the same somewhat flexible while at the same time stiff enough to afford a very satisfactory means of connection for the electrical circuit.

Another important object of the invention is the provision in an electric light plug or the like of means incorporated into the body of the plug for retaining the contact prongs while at the same time allowing the same to be readily removed and replaced, if desired or necessary.

Another and still further important object of the invention resides in the incorporation into a plug of this sort of means for readily grasping the same when it is desired to withdraw it from a connecting socket or the like, whereby undue strain on the wire and connections is lessened or eliminated.

Other and further important objects of the invention will be apparent from the disclosures in the accompanying drawing and following specification.

The invention, in a preferred form, is illustrated in the drawing and hereinafter more fully described.

In the drawing:

Figure 1 is a sectional view of the improved soft rubber plug of this invention, showing the interior arrangement.

Figure 2 is a top plan view of the same.

Figure 3 is a perspective view of one of the contact prongs.

Figure 4 is a plan view of the ring which is embedded in the plug for supporting the contact prongs.

Figure 5 is a sectional view looking upward illustrating a slight modification.

Figures 6 and 7 show further modifications of the ring.

As shown in the drawing:

The reference numeral 10 indicates generally the body of the plug which is preferably composed of soft or semi-soft rubber molded into the shape as shown, and having a central opening 12 extending therethrough for the reception of cur-

rent-carrying wires. It will be noted that the rear end of the body is elongated and is formed with an annular bead or the like 14 whereby the same can be readily grasped by the fingers and undue strain on the wires is eliminated, especially when the plug is being withdrawn from a wall socket or current-carrying receptacle.

Embedded in the body 10 and preferably incorporated thereto at the time of molding is a flat ring 16 preferably composed of fiber or some similar fairly stiff and insulating material, this ring being disposed concentrically with the opening 12 and having a set of holes 15 therein provided for the reception of prong fastening screws or the like 18. Screws 30 acting as binding posts for the reception of current carrying wires are fitted into holes 19 in the ring and pass through corresponding openings in the contact prongs.

If desired, the ring may be made in two pieces, one for each side of the plug as shown at 17 in Figure 5, and in the event that these pieces are separated by portions of the plug body itself, they need not under those circumstances be composed of insulating material, but may be made of metal. If the elements 17 are composed of metal, the openings for the screws 18 and 30 will obviously be positioned closer together, but if the elements 17 are composed of fiber or other insulating material, the screw openings will be as shown inasmuch as the contact prong feet 22 with the screws will then bridge the gap between the adjacent ends of the sections 17, as is obvious from an inspection of Figure 5, the spacing of the large and small holes in the individual halves of the rings are such that the large hole in one half and the small adjacent hole in the other half, take the two screws which pass thru the contact prong feet. As shown in Figure 5, the half sections would necessarily be made of fiber or other insulation material in order to avoid short circuiting of the prongs.

Each of the screws 18 is adapted to retain the contact prong 20 in position on the plug, these contact prongs being shaped as best shown in Figure 3 and having a base 22 extending at right angles to the prong portion, one edge of the base being curved to correspond with an upwardly projecting annular lip 24 integral with the body 10 of the plug.

Each of the bases 22 of the contact prongs is provided with a pair of openings 26 and 28, the openings 26 being for the reception of the fastening screw 18 and the other opening being for the reception of the wire attaching screw 30. The

wire attaching screws 30 are adapted to pass through the foot 22 of the contact elements and into the sockets or depressions 34 formed in the body of the plug 10 as best shown in Figure 1, and 5 also into the fibre disk, furnishing additional means of fastening for the prong.

It will be evident that herein is provided a soft rubber electric light plug which being composed of a minimum of parts can be readily manufactured and assembled, is not likely to get out of order, and which furthermore, will be highly satisfactory from the user's point of view. The ring 16, being of fiber or the like, is stiff enough to properly position the contact prongs with relation to the plug and to each other, and even though the ring is made in two sections, the body of the plug may be made sufficiently solid for proper positioning purposes. The screws 18 can ordinarily cut their own threads in openings in 20 the fiber ring 16, but, of course, these openings can be previously threaded, if desired.

In Figure 6 is shown a ring 32 with a plurality of holes 34 formed therein. When the plug body is molded around such a ring, the rubber, being 25 plastic, will flow into the holes 34, thereby securely locating and fixing the ring in the plug body. Figure 7 illustrates a ring 36 having notches 38 cut into its periphery whereby a more complete flowing of the plastic rubber around and 30 about the ring is insured.

In this plug, the contact prongs are seated on a body which is relatively soft and flexible, and the prongs themselves are fastened to a permanently embedded disk or disk-like sections by an 35 intermediate fastening means so that the contact prongs are yielding and distortable. These prongs are separated from the embedded disk or disk sections by a thickness of flexible material. This three-part assembly provides a very flexible 40 fastening arrangement which is yielding and distortable without permanent misalignment.

I am aware that many changes may be made and numerous details of construction varied throughout a wide range without departing from 45 the principles of this invention, and I, therefore, do not purpose limiting the patent granted hereon otherwise than as necessitated by the prior art.

I claim as my invention:

1. An electrical connector plug, comprising a 50 soft rubber like body having an opening extending longitudinally therethrough for the passage of wires, a non-conducting ring embedded in the body, and contact prongs fastened to and positioned by the ring, feet integral with the contact 55 prongs and screws passing through the contact prong feet and into the ring for mounting the same, together with wire-attaching screws on the contact prong feet.

2. An electrical connector plug, comprising a 60 soft rubber like body having an opening extending longitudinally therethrough for the passage of wires, a non-conducting ring embedded in the body, and contact prongs fastened to and positioned by the ring, and screws passing through 65 the contact prongs and into the ring for mounting the same, together with wire-attaching screws on the contact prongs, the plug having sockets therein for the reception of the ends of said wire-attaching screws.

3. An electrical connector plug, comprising a 70 soft rubber like body having an opening extending longitudinally therethrough for the passage of wires, a non-conducting ring, embedded in the

body, and contact prongs fastened to the ring, said contact prongs provided with integral foot members and screws for fastening the foot members to the seating ring.

4. An electrical connector, comprising a soft 5 rubber body, a non-conducting ring embedded in the body, a pair of contact prongs on the body and removably fastened to the ring, each of said contact prongs provided with an integral foot element adapted to be applied against the outer 10 face of the plug.

5. An electrical connector, comprising a soft rubber body, a non-conducting ring embedded in the body, a pair of contact prongs mounted on the body and removably fastened to the ring, 15 each of said contact prongs provided with an integral foot element adapted to be applied against the outer face of the plug, and a projecting annular lip integral with the plug body surrounding said foot elements, said foot elements separated from each other by air spaces.

6. In a soft rubber plug comprising a unitary body, contact prongs, feet on the prongs, and means for positioning the contact prongs, said means comprising a relatively stiff sectional ring 25 molded in the plug body, and means connecting the contact feet to the ring.

7. In a soft rubber plug, contact prongs, feet on the prongs, and means for positioning the contact prongs, said means comprising a relatively 30 stiff two-piece ring of insulating material molded in the plug body, and screws on each contact prong foot connecting adjacent portions of the ring to the foot.

8. A soft rubber electric plug, contact prongs 35 on the plug, and means for positioning the prongs, said means comprising relatively stiff elements permanently embedded in the plug body, and means connecting the contact prongs to said elements, together with binding post screws in the contact prong supports, said binding post screws additionally connecting the contact prong supports to the positioning elements.

9. A soft rubber electric plug, contact prongs on the plug, and means for positioning the prongs, 45 said means comprising relatively stiff elements permanently embedded in the plug body, and means connecting the contact prongs to said elements, together with binding post screws in the contact prong supports, said binding post screws 50 additionally connecting the contact prong supports to the positioning elements, the first-named connecting means between the contact prongs and the elements comprising additional screws.

10. An electrical connector, comprising a soft 55 rubber body, a non-conducting ring embedded in the body, a pair of contact prongs wholly outside the body, and removably fastened to the ring.

11. An electrical connector, comprising a soft rubber body, a non-conducting ring embedded 60 in the body, a pair of contact prongs wholly outside the body, and removably fastened to the ring, and means for additionally securing the contact prongs to the ring, said means further comprising binding posts for the ends of conductor wires. 65

12. An electrical connector, comprising a soft rubber body having a passage therethrough for conductor wires, a non-conducting ring embedded in the body and encircling said passage, a pair of contact prongs wholly outside the body, and removably fastened to the ring. 70
